ELMER H. CHANDONIA, OF CINCINNATI, OHIO, ASSIGNOR TO THE LOCKWOOD MANUFACTURING COMPANY, OF CINCINNATI, OHIO, A CORPORATION OF OHIO

MULTIPLE BAKE PAN

Application filed November 17, 1930. Serial No. 496,092.

This invention relates to multiple bake pan unit construction including a novel form of pan connecting means or encircling band.

An object of the invention is to provide a simple and inexpensive means on bake pan units for strengthening the corners, where they are subject to the greatest abuse, without increasing the thickness of metal at such corners.

10 Another object is to provide a means for the purpose stated which serves also to provide a support at the four corners of a pan unit for assisting in bearing the weight of a stack of nested units, thereby precluding distortion of the pan units.

These and other objects are attained by the means described herein and disclosed in the accompanying drawing, in which:

Fig. 1 is a side elevational view of an improved bake pan unit nested with a similar unit, part being broken away.

Fig. 2 is an end elevational view of one of the pan units.

Fig. 3 is an isometric view of an encircling band of novel design.

Fig. 4 is a fragmentary view showing a modified form of side element or band.

In Fig. 1 is disclosed two sets, or units, 4 and 5, of connected bake pans, the pans of unit 4 being indicated by characters 40, 41 and 42, and the pans of unit 5 being represented at 50, 51 and 52. Any reasonable number of such pans may comprise a pan unit, groups of four and eight pans being common. It is common practice also to turn the free upper edges 6 of the pan walls upon a wire or other strengthening frame 7 encircling the pans individually to form a bead, but this construction may be varied as it forms no part of the present invention. It is desirable, however, to provide some sort of bead, such as 8, against which the bead 9 on the upper peripheral edge of the encircling band 10 may abut, thereby providing a rigid and solid construction.

The encircling band is shown in detail in Fig. 3, and it may comprise a pair of end elements or straps 12 and 13, connected to one another by means of a pair of side elements or straps 14 and 15 connected to the

inwardly turned ends 16 of the end elements, by any suitable means such as rivets 17. It is to be understood that the inwardly turned ends may be formed on the side elements instead of on the end elements, as indicated in Fig. 4 wherein 150 represents a side element or strap, 160 the inwardly turned end, and 161 the rivet hole. It is to be understood further that the side and end elements may be formed as a unit, of a continuous strip of material, if desired.

As shown in the drawing, means are provided whereby the end walls of the pans are attached to the side bands, and said means may vary depending on whether the pans are of the pressed or drawn seamless type, or of the folded sheet type. The folded sheet type is disclosed herein, and the attaching means are shown as clinch lugs 18, formed from the material of the side band and adapted to cooperate with the folds 19 of the pan end walls, as being a preferred form of the invention. The characters 20 indicate openings for reception of rivets or other fastening means.

Each of the four corners of the encircling band or pan support 10 is provided with a transverse outwardly extending rib or projection 21, which extends outwardly beyond the normal outer limits of the encircling band. These ribs or projections may be formed by pressing the material of the band outwardly to form a U, or other shape (such as a V), extending preferably from the bead 9 to the opposite or lower edge 22 of the encircling band, whereby to provide added strength and protective bumpers at the corners of the unit. These projections also serve to carry a share of the weight when a number of units are nested, for they rest upon the top edges of the corners of a subjacent pan unit, as is clearly shown in Fig. 1. As indicated in Figs. 3 and 4, the projections 21 may be formed on either the end elements 12 or the side elements 150.

The lower edges 22 of the encircling band may be turned inwardly to form a flange as indicated at 23 to provide for a line contact of the encircling band upon the pan walls, whereby to provide for an air space between

the band and walls to insure uniform heat penetration and radiation during and after use, respectively, of the pan units. Suitable types of end bumper plates, (not shown) 5 may be attached to the ends of the pan units in any well known manner, without interfering with the means of the present invention.

What is claimed is:

1. In combination with a unit comprising 10 a plurality of substantially parallel bake pans, an angular encircling supporting band for supporting the bake pans, said band having projections at its corners formed by the metal of the band bent outwardly upon itself to provide a corner protector spaced from the pan corner edges and extending sufficiently downwardly and outwardly beyond the normal limits of the band, 15 to rest upon the tops of corresponding corner portions of a subjacent similar set of nested pans.
2. In combination with a unit comprising 20 a plurality of substantially parallel bake pans, an angular encircling supporting band for supporting the bake pans, said band having projections at its corners formed by the metal of the band bent outwardly upon itself to provide a corner protector spaced from the pan corner edges and extending sufficiently 25 beyond the normal limits of the band to rest upon corresponding corner portions of a subjacent similar set of nested pans, and a peripheral extending bead on the band.
3. An angular encircling supporting band 30 for supporting bake pans, said band having projections at its corners formed by the metal of the band bent outwardly upon itself to provide a corner protector spaced from the pan corner edges and extending sufficiently 35 beyond the normal limits of the band to rest upon corresponding corner portions of a subjacent similar set of nested pans, and a peripheral extending bead on the band integral with the projections.
4. In combination with a unit comprising 40 a plurality of substantially parallel bake pans, a pair of side band members each having inwardly turned ends forming a corner of the unit, said corner being formed by the metal of the band bent outwardly upon itself to provide a corner protector spaced from the pan corner edges and extended sufficiently 45 beyond the normal limits of the band to rest upon corresponding corner portions of a subjacent similar set of nested pans, and bands secured to the inwardly turned ends of the side band members for providing an encircling band for the group of 50 pans, and means on the encircling band for attaching the band to the pans.
5. In combination with a unit comprising 55 a plurality of substantially parallel bake pans, an angular encircling supporting band for supporting the bake pans, said band having 60 projections at its corners formed by the

metal of the band bent outwardly upon itself to provide a corner protector spaced from the pan corner edges and extending sufficiently beyond the normal limits of the band to rest upon corresponding corner portions of a subjacent similar set of nested pans.

In testimony whereof, I have hereunto subscribed my name this 14th day of November, 1930.

ELMER H. CHANDONIA.
